BRASSIÈRE

Sydne Cousins, Far Rockaway, N. Y.

Application April 5, 1951, Serial No. 219,493

4 Claims. (Cl. 2—42)

1

This invention relates to garments for molding and supporting the breasts, and which will, for convenience be referred to as "brassières," it being understood that they may comprise undergarments, parts of undergarments, outer garments or parts of outer garments. More particularly, the present invention is concerned with a brassière including a pair of abbreviated bust cups, each of which is characterized by the absence of what normally would be the upper half thereof; that is to say, a bust cup in which the upper edge is at approximately the level of the tip of the breast accommodated thereby.

It is an object of my invention to provide a brassière of the character described which despite the absence of the upper halves of the bust cups maintains an excellent degree of control over the breasts.

It is another object of my invention to provide a brassière of the character described which although greatly freeing the breasts by exposing their upper portions, yet retains control over almost substantially all of the base of each breast, thereby firmly determining the location of the breasts and preventing untoward movement thereof arising from movement of the wearer's torso.

It is a more particular object of my invention to provide a brassière of the character described in which the bust cups are abbreviated only in their covering portions, that is to say, only in the portions which cover the mounds of the breasts.

It is an even more specific object of my invention to provide a brassière of the character described in which the controlling means for the upper exposed half of each breast is a stiff frame so that the control is exerted in a predetermined manner and in a predetermined location, not left to the chance disposition of a flexible tape or the like.

It is an ancillary object of my invention to provide a brassière of the character described which by virtue of the bust cup construction used to obtain controlled freedom of the breasts is able to employ a very low back.

It is another ancillary object of my invention to provide a brassière of the character described which is so constructed that it is not necessary to employ a full underarm panel or back in order to maintain satisfactory control of the side line of each breast.

Other objects of my invention will in part be obvious and in part will be pointed out hereinafter.

5

My invention accordingly consists in the features of construction, combinations of elements and arrangements of parts which will be exemplified in the brassières hereinafter described and of which the scope of application will be indicated in the appended claims.

In the accompanying drawings in which are shown various possible embodiments of my invention:

Fig. 1 is a front perspective view of a brassière constructed in accordance with the present invention, the same being shown as it appears on a lay figure;

Fig. 2 is an enlarged fragmentary view in partial section of one of the bust cups of said brassière;

Figs. 3 and 4 are sectional views taken substantially along the lines 3—3 and 4—4, respectively, of Fig. 2; and

Figs. 5 and 6 are views similar to Figs. 1 and 2, respectively, of a brassière embodying a modified form of my invention.

In general, I carry out my invention by having each bust cup include a semi-dome-shaped portion; that is to say, a dome-shaped portion which is truncated by a substantially horizontal plane at about the level of the tip of a breast to be accommodated in the bust cup. A stiff skeleton frame extends upwardly from both side edges of the semi-dome-shaped portion; this frame being an integral part of the bust cup. The bust cup is abbreviated in that the upper half of the domed portion normally serving as a cover for a breast has been eliminated; however, a substantial portion at least of the base of the upper half of the bust cup is retained in the form of said frame. The frame exerts a retaining or controlling force on the upper half of the base of a breast without, however, confining movement of the surface of said upper half. The frame preferably extends down at least to approximately the level of the lowest part of the base of the breast so that the semi-dome-shaped portion together with the reinforcing frame constitutes a complete unit capable of exerting a desirable molding function when held against the rib cage.

Due to a provision of such a unit it is not necessary, as it is in conventional brassières, to exert a circumferential pull over a substantial extent of the outer side of a bust cup in order to hold the outside wall of the cup in position.

Referring now in detail to the drawings, and more particularly to Figs. 1—4, the reference numeral 10 denotes a brassière comprising two bust cups 12, 14 whose construction constitutes the

2

principal feature of my invention. Inasmuch as the bust cups are mirror images of one another, only the cup 14 will be described in detail, and the same reference numerals primed will be applied to the other cup 12.

The bust cup 14 includes a semi-dome-shaped portion 16. In the preferred form of my invention said portion is fabricated from a sheet material which is capable of maintaining its own shape when doffed. Typical materials are a plastic impregnated cloth sheet or a plastic sheet a few thousandths of an inch thick, desirably a plastic strong enough to hold a semi-dome-shaped contour to which it is formed as by molding, but including sufficient amounts of plasticizer, as is well known in the art, to render the portion 16 somewhat yielding whereby it will not be uncomfortable to wear. The plastic material, nevertheless, will tend to make a breast accommodated thereby conform to its shape rather than having the portion 16 conform to the shape of the breast so that said portion controls the shape imparted to a breast.

Said dome-shaped portion includes a lower edge 18, an inner side edge 20, an outer side edge 22 and a top edge 24. The lower edge 18 is horizontal and substantially straight as viewed from the front (see Fig. 2), and is slightly curved as viewed from the top (see Fig. 3) to approximately conform to the curvature of a rib cage at the level of the lowermost part of the base of a breast. The upper edge 24 is at approximately the level of the top of a breast. Said upper edge may be slightly convex upwardly as indicated in Fig. 2 although the same is not essential to the practice of my invention. Indeed, if desired, this edge may be slightly concave or may be concave only over a central portion, as indicated at 26 in Fig. 5.

The inner side edge 20 slopes downwardly and inwardly at a slight angle to the vertical as shown in Fig. 2 and the outer side edge 22 likewise slopes downwardly and inwardly. These two side edges are substantially tangent to the base 28 of a breast, the inner side edge 20 being a little lower than the outer side edge 22 so that said inner side edge is tangent to the base of the breast at a point approximately level with or a little below the tip, whereas the outer side edge 22 is tangent to the base of the breast at a point a little above the tip. This length of the outer side edge affords an excellent support at the outer sides of the bust where there is a tendency for control to be lost and for the breasts either to spill over or creep out from underneath the bust cups.

It should be noted that the foregoing detailed description of the semi-dome-shaped portion has been given by way of example only, and is not to be construed as limitative except to the extent indicated in the claims.

Pursuant to the principal feature of my invention the bust cup 14 includes a frame having an element on each side of the semi-dome-shaped portion 16. Any suitable type of frame may be employed, for example, a metal or plastic wire, the particular novelty residing in the fact that the frame extends by itself above the upper edge 24 of the semi-dome-shaped portion and thereby constitutes a skeleton top, that is to say, a top, which with the upper edge 24, defines an open space, i. e. a space uncovered by any restraining sheet material. The frame elements are stiff in the sense that they do not yield readily to stress and in this respect are similar to

the reenforcing members of conventional wired brassières.

More specifically, the skeleton frame includes a pair of stiff wires 30, 32. Each of said wires 5 has a lower half running along either an inner or an outer side edge of the semi-dome-shaped portion and extending from the bottom edge 18 to the top edge 24. This lower half serves to reinforce the side edges of said semi-dome-shaped portion and hold the same firmly against the usual distorting forces. Each wire 30, 32 further includes an upper half which projects above the upper edge 24. Although the lower half of each wire, because it extends along the straight inner and outer side edges 20, 22, itself 15 is straight and therefore tangent to the base of the breast at approximately the level of the tip, the upper half of each wire is outwardly convex so that the wires curve towards each other following the contour of the upper half 20 of the base of the breast, as best seen in Fig. 2.

The wires 30, 32 may extend all the way from the upper end of one side edge to one upper end of the other side edge. However, in the illustrated form of my invention said wires terminate 25 short of the uppermost part of the base of the breast and thus afford a degree of freedom to the wearer, there being little or no necessity for positional control over this zone of the breast.

Suitable means is employed to hold the wires 30 in their aforesaid positions. Such means may comprise a tape 34 folded in half along its longitudinal center line to bring its edges into registry. The tape is sewed together adjacent said 35 edges, as by a row of stitching 36, whereby to form a cloth tube within which the wires 30, 32 are contained. Said tube and the lower halves 35 of the wires are placed adjacent the side edges of the semi-dome-shaped portion, and flaps 38 40 (Fig. 3) integral with said edges are folded around to form pockets within which the tapes and wires are disposed. Stitching 40 holds the flaps 38 in position and secures the tape and wires to the semi-dome-shaped portion. This arrangement further provides a flexible limp connection between the tops of the two wires. Due to the comparatively short span of said cloth element, the same tends to follow the general contour of the uppermost part of the base of the breast.

Said cloth element has secured thereto, as by tack stitching, one end of a shoulder strap 41 whose other end is attached to the back of the brassière in a conventional manner.

The two bust cups 12, 14 are connected to one another over the sternum in any suitable fashion as, for instance, by a pair of crossed elastic tapes 42.

Means also is included to hold the brassière 60 in position on the rib cage. Said means includes a tape 44 extending from the bottom end of an outer side edge 22 of one of the bust cups around the back of the wearer to the corresponding point on the outer side edge of the other bust cup. The tape is interrupted in the back of the brassière by a conventional rapid detachable coupling means as, for instance, hooks and eyes, to permit the brassière easily to be doffed and donned. Said tape preferably includes an elastic section. Another tape 46, which may be elastic, is connected from adjacent the upper end of the outer side edge of the bust cup to the tape 44 at a point removed from the bust cup, e. g. in the 65 underarm region of the body, whereby the back

of the brassière is particularly low, permitting a deep back decolletage.

I have observed that the lower halves of the wires 30, 32 function to firm the softer material of the semi-dome-shaped portions and thus enable said portions to hold their desired curvature and shape. Moreover, I have found that the upper halves of the wires, where the frame is nothing but a skeleton, act to positionally control the base of a breast in a positive manner and thereby prevent the same from shifting or falling out of the semi-dome-shaped portion 16. In other words, I have discovered that full control of the upper half of a breast can be obtained simply by controlling the location of the base of the breast alone for a substantial distance upward from the level of the tip. This type of control, although firm and positive, nevertheless permits surface freedom of the upper half of the breast inasmuch as the same is not covered by the semi-dome-shaped portion and, further, since, as illustrated in the preferred form of my invention, the upper ends of the wires are not firmly interconnected. Thus, I have created a practical brassière which provides a natural, round and youthful appearance to the bust line with definite assurance that the breasts cannot spill out. In other words, the instant brassière separates the breasts, rounds each breast and holds each breast firmly in position. Furthermore, by carrying a substantial part of the weight of each breast in a semi-permanently fashioned bust cup the strain on the shoulder strap is greatly reduced.

It should be noted that, because the skeleton frame extends both above and below the upper edge 24 of the semi-dome-shaped portion the bust cups will function properly if the same are held in place only at the lower ends of the wires 30, 30' on the outer side edges 22, 22' of the two bust cups, the tops of the bust cups being held in position on the rib cage by the shoulder straps. That is to say, despite the fact that the bust cups are semi-dome-shaped there is no tendency for said cups to fall forward under the weight of the breasts, such tendency being restrained by the presence of skeleton frames such as described. On the other hand, in a conventional brassière having no skeleton frame projecting above the level of the nipple, the tendency for the bust cup to lean forward must be overcome by heightening the underarm and back of the brassière and thus preventing the extremely low decolletage which is obtained with a brassière such as herein described.

If desired, a plush ribbon 43 may be employed to line the inner face of the semi-dome-shaped portion adjacent the bottom edge 18.

The brassière can be variously changed without departing from the spirit of my invention. For example, as shown in Figs. 5 and 6, a modified brassière 50 embodying the present invention includes a semi-dome-shaped portion 52 which is covered on its front face with a layer 54 of cloth or lace for decorative purposes. Said portion instead of being molded or pressed in a curved shape can be formed to the desired contour from a flat plastic sheet with the aid of a dart 56.

The brassière 50 has no shoulder straps. Accordingly, to exert the requisite degree of control over the uppermost part of the top half of each breast, wires 58, 60 on each bust cup extend further upwardly than the corresponding wires in the brassière 10. Moreover, the upper ends of the wires 58, 60 are more firmly intercon-

nected as, for instance, with a helical spring 62 which is nested in the tubular tape 64 covering the wires.

It thus will be seen that I have provided devices which achieve all the objects of my invention and are well adapted to meet the conditions of practical use.

As various possible embodiments might be made of the above invention, and as various changes might be made in the embodiments above set forth, it is to be understood that all matter herein described or shown in the accompanying drawings, is to be interpreted as illustrative and not in a limiting sense.

Having thus described my invention, I claim as new and desire to secure by Letters Patent:

1. In a brassière, a pair of bust cups, each of which includes a semi-dome-shaped portion whose upper edge is approximately level with a tip of a breast accommodated thereby, a pair of stiff skeleton members extending upwardly from both side edges of the bust cup substantially above and clear of the upper edge thereof, said members following the contour of the upper half of the base of the breast, and defining in conjunction with said upper edge an empty uncovered space, whereby the base of the upper half of the breast is positionally controlled without confining the surface of the same, said members having upper ends which are located above and on opposite sides of the tip of the breast whereby said upper ends are spaced apart, and a limp element interconnecting said upper ends.

2. In a brassière, a pair of bust cups, each of which includes a semi-dome-shaped portion whose upper edge is approximately level with a tip of a breast accommodated thereby, a pair of stiff skeleton members extending upwardly from both side edges of the bust cup substantially above and clear of the upper edge thereof, said members following the contour of the upper half of the base of the breast, and defining in conjunction with said upper edge an empty uncovered space, whereby the base of the upper half of the breast is positionally controlled without confining the surface of the same, said members having upper ends which are located above and on opposite sides of the tip of the breast whereby said upper ends are spaced apart, and a spring interconnecting said upper ends.

3. In a brassière, a pair of bust cups, each of which includes a semi-dome-shaped portion whose upper edge is approximately level with a tip of a breast accommodated thereby, a pair of stiff skeleton members extending upwardly from both side edges of the bust cup substantially above and clear of the upper edge thereof, said members following the contour of the upper half of the base of the breast, and defining in conjunction with said upper edge an empty uncovered space, whereby the base of the upper half of the breast is positionally controlled without confining the surface of the same, said members having upper ends which are located above and on opposite sides of the tip of the breast whereby said upper ends are spaced apart, the tips of said members being spaced apart, and a helical spring interconnecting said upper ends.

4. In a brassière, a pair of demi-bust cups, the upper edge of each of which is approximately level with the tip of the breast accommodated thereby, a pair of skeleton frame members running along both side edges of each bust cup and extending upwardly from said side edges substantially above and clear of the upper edge

thereof and defining in conjunction with said upper edge an empty uncovered space, whereby the base of the upper half of the breast is positionally controlled without confining the surface of the same, said members having upper ends which are located above and on opposite sides of the tip of the breast whereby said upper ends are spaced apart, and a limp element interconnecting said upper ends.
